United States Patent Office

Des. 182,704
Patented May 6, 1958

182,704

COVER KNOB FOR DISHES AND THE LIKE

Ralph B. Billig, Westlake, and Manuel S. Ziskin, Mayfield Heights, Ohio, assignors to Kromex Corporation, Cleveland, Ohio, a corporation of Ohio

Application August 15, 1957, Serial No. 47,377

Term of patent 14 years

(Cl. D44—15)

FIG. 1

FIG. 2

Fig. 1 is a top plan view of a cover knob for dishes and the like showing our new design; and

Fig. 2 is an elevational view thereof.

We claim:

The ornamental design for a cover knob for dishes and the like, as shown and described.
